UNITED STATES PATENT OFFICE

LAURENCE ARTHUR VINCENT, OF PLEASANTVILLE, PENNSYLVANIA, ASSIGNOR, BY MESNE ASSIGNMENTS, TO NEW CASTLE REFRactories COMPANY, OF NEW CASTLE, PENNSYLVANIA, A CORPORATION OF DELAWARE

DEVICE FOR SUPPORTING TABLEWARE IN A KILN

Application filed February 6, 1928. Serial No. 252,073.

The object of my present invention is to provide improved apparatus for supporting table ware in kilns of the type in which the products of combustion from the kiln heating system do not contact with the ware being fired. A further object of my invention is to provide improved table ware supporting means which are so constructed that the ware to be fired can be placed in the ware supports and the supports placed on the car at a loading station and unloaded from the car at a second station with a minimum loss of ware and ware supports due to breakage.

The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described preferred embodiments of the invention.

Of the drawings:

Fig. 1 is an elevation partly broken away of one form of my invention;

Fig. 2 is a section on the line 2—2 of Fig. 1;

Fig. 3 is an elevation partly in section of a modification;

Fig. 4 is a section on the line 4—4 of Fig. 3;

Fig. 5 is an elevation partly in section of a second modification;

Fig. 6 is an elevation of a third modification; and

Fig. 7 is a plan view of a fourth modification.

In the drawings and particularly in Figs. 1 and 2 I have illustrated a preferred form of ware support in which the supporting frame or rack comprises a top frame A and a bottom frame B, each of which is in the form of an open triangular frame having an enlarged boss C at each corner thereof. Each boss is formed with a recess C' for receiving one end of a pillar or post D.

In the preferred construction each post D is formed with a number of horizontally inclined recesses E vertically spaced from one another. Each recess has an enlarged portion E' triangular in cross-section extending

inwardly and upwardly and a small passage E² connecting the outer end of the portion E' to the outer face of the post. As shown in Fig. 1 a small pin F triangular in cross-section and made of refractory material is 55 adapted to be inserted in each recess E to provide a point of support for one of the ware pieces.

Ware supporting structures heretofore in use have generally been made of refractory material to withstand the high kiln temperatures. Structures so constructed have not proved satisfactory in practice because of the heavy losses due to breakage in handling operations. Such supports have been so fragile in construction as to practically prohibit any method of loading except that of placing the ware supports on the kiln car and then loading the supports with the ware to be fired. The ware support of my present invention is 60 preferably made of a high temperature resistant alloy and the support may be loaded with ware before being placed on the car and handled with practically no loss due to breakage. Iron and nickel chromium alloys are 65 suitable for this purpose, and an alloy composed of 65% nickel and 35% chrome has been found to be particularly satisfactory.

I have found that when a metal construction is used, it is preferable to construct each post in two parts D', each semi-elliptical in cross-section, to eliminate the difficult and costly coring operation necessary in producing the recesses in the post.

As shown in the parts of Fig. 1 broken away, the flat face of each of the post members is formed with vertically spaced grooves e' each of which is half the cross sectional area of the recess formed when the two parts are connected with the corresponding grooved portions of each part in proper contact. The post members may be joined together in any suitable manner such as by spot welding at vertically spaced points D³ as shown in Fig. 1. A projection D⁴ is formed at each end of each post and composed of two projecting members d⁴ semi-circular in cross section formed on the post members D'. The combined members are 95 inserted in the recesses C' formed in the bot-

tom and top plates and preferably welded in position. The clay pins F are then inserted in the recesses and the ware support is ready to be loaded. The pins are removed and discarded after each burn. The small passage E² forming the outer end of each recess permits the insertion of a tool to eject the clay pins from the recesses when necessary.

In Figs. 3 and 4 I have illustrated a modified form of metallic construction in which the posts are formed of metallic rods H circular in cross-section. The top and bottom plates are constructed substantially the same as in Figs. 1 and 2 except that the top frame is 10 removably mounted on the posts and the bottom frame recesses are continued to the lower face of the bosses. In this construction a multiplicity of clay pieces K having four radial arms K' constituting ware supporting points projecting from a hub K² are removably mounted on each of the rods H. Each clay piece may be revolved on the corresponding rod H to provide a new supporting point for each burn. The clay pieces illustrated 20 may thus be used for four successive burns before being discarded.

In the construction shown in Figs. 5 and 6 each metallic post M is cast in a single piece with metallic members N projecting at an 30 angle therefrom. It has been found impractical to use a metallic supporting point for the ware pieces owing to the tendency of the metal to discolor the glaze during the heating treatment. Ceramic bodies having a point contact are therefore provided for this purpose. In Fig. 5 a removable clay cap O is fitted over the tapered end of each of the metallic projecting members N and is replaced after each burn. In the construction 35 shown in Fig. 6 a clay pin P is placed in a recess N' formed in the inner face of each of the projecting members N. These pins must also be replaced after each burn.

The various supporting frames illustrated 45 may be constructed for supporting one or more bungs of ware and in Fig. 7 I have illustrated a supporting frame Q for supporting two bungs of plates. In this construction the top and bottom frames are each made in a unitary structure in the form of two open triangles contacting at their apices and having a cross-piece R connecting two of the remaining corners to form a substantially 50 equilateral triangle. The posts used in this construction can be any of the constructions described except that the post S mounted at the junction of the apices of the triangular frames is of general triangular cross-section with recesses S' formed in adjacent sides for 55 two sets of clay supporting pins. The post S is thus utilized in supporting each of the bungs of ware.

My invention is characterized by the ease 60 in which the ware supports are made and assembled at a relatively low cost of production.

The ware supports can be placed on the cars in tiers of two or more thereby increasing the carrying capacity of the kiln cars. The increased strength of the unitary construction permits the ware to be loaded before 70 the supports are placed on the cars and removed therefrom while in the supports. This is advantageous in materially increasing the speed and lowering the cost of the loading and unloading operations. While the constructions shown are preferably made of heat resistant alloy due to its strength and heat resistant properties, it may be possible to use a refractory mixture having sufficient 75 strength which would be cheaper than the 80 alloy construction.

While in accordance with the provisions of the statutes, I have illustrated and described the best form of embodiment of my invention now known to me, it will be apparent 85 to those skilled in the art that changes may be made in the form of the apparatus disclosed without departing from the spirit of my invention as set forth in the appended claims and that in some cases certain features 90 of my invention may be used to advantage without a corresponding use of other features.

Having now described my invention, what I claim as new and desire to secure by Letters Patent, is:

1. A structure for supporting a multiplicity of ceramic articles during a heat treating process comprising top and bottom frame members, a plurality of posts connected to said frame members, one of said posts comprising a plurality of parts shaped to provide a series of vertically spaced substantially horizontal recesses when said parts are connected, and ware supporting pins 10 mounted in said recesses.

2. A structure for supporting a multiplicity of ceramic articles during a heat treating process comprising top and bottom frame members, a plurality of posts connected to said frame members, one of said posts comprising a plurality of parts composed of a heat resistant alloy and shaped to provide a series of vertically spaced substantially horizontal recesses when said parts are connected, and ware supporting pins 10 removably mounted in said recesses.

3. A support for ceramic articles during a heat treating process comprising top and bottom frame members, a plurality of vertical posts connected to said frame members, one of said posts having a series of vertically spaced horizontally extending recesses opening to the inner side of the post, ware supporting pins positioned in said recesses and abutting the outer ends thereof, and a passage of substantially reduced and uniform cross-sectional area extending from the outer end of each recess to the outer side of the post, whereby a tool may be inserted from the 11

outer side of the post for dislodging a ware supporting pin mounted in any of said recesses.

4. A support for a plurality of bungs of ceramic articles during a heat treating process comprising top and bottom open frame members, a plurality of vertical posts extending between said frame members at horizontally spaced points, a series of vertically spaced ware supporting pins projecting inwardly from each of said posts, and an intermediate post having a second series of said pins, said posts and pins being arranged to provide a three point support for each of said articles.

Signed at Cleveland, in the county of Cuyahoga and State of Ohio, this 3rd day of February, A. D. 1928.
